UNITED STATES PATENT OFFICE.

RUSSELL V. JUDSON, OF DETROIT, MICHIGAN.

CENTRIFUGAL SORTING MACHINE.

Application filed April 7, 1923. Serial No. 630,667.

This invention relates to centrifugal sorting machines adapted for use with various grains or seeds, such as beans, peas, clover seed and the like, and its purpose is to provide a construction especially suited to a machine of small size and medium capacity such that it can be manufactured economically and will operate with greater efficiency than previous machines of this general type. It consists of the various features and elements of construction and their combination, as herein described and shown in the drawings, and as indicated by the claims.

In the drawings:

Figure 1 is a vertical, axial section of a machine embodying this invention.

Figure 2 is a top plan view, with the feed hopper removed and with certain parts broken away and shown in section.

Figure 3 is a vertical axial section through one of the rolls, as indicated at line, 3—3, on Figure 2.

Figure 4 is a detail section taken as indicated at line, 4—4, on Figure 2.

Figure 5 is a vertical axial section taken through another roll, as indicated at line, 5—5, on Figure 2.

Figure 6 is a transverse section through a pair of rolls and the cover casting taken at line, 6—6, on Figure 2.

This machine is of the centrifugal type, operating on substantially the same principle as the machine shown in my Patent No. 1,366,665, dated January 25, 1921, and comprising several pairs of rolls of yielding material, arranged in radiating relation to a vertical axis of revolution, so that the beans or other grain to be sorted, if fed on to the rolls near said axis, are carried outward over the rolls by centrifugal force, while the rough or imperfect specimens and the particles of dirt mixed in with them are frictionally engaged by the yielding rolls and drawn between them for discharge separately from the smooth grain which successfully traverses the rolls to their outer ends.

In the present structure, I provide a central supporting column, 1, extending upwardly from the base or supporting casting, 2, and supporting near its upper end a cast member comprising a sleeve portion, 3, which fits the column, 1, and is attached thereto by one or more bolts, 4, and a flared portion, 5, whose upper edge is formed with gear teeth at 6 to mesh with beveled drive pinions, 7, of the several pairs of rolls. The

sleeve portion, 3, provides a shoulder, 8, upon which is lodged a ball thrust bearing, 9, to support rotatively the central hub, 10, of the rotor or frame casting which supports the rolls and serves also as a cover for them. This rotor casting includes an annular upwardly flange, 11, forming a central hopper provided with a removable bottom plate, 12, onto which the grains are delivered by gravity from a feed hopper, 13, and from which they are moved by centrifugal force to discharge ports, 14, each of which leads to the trough formed between a pair of the picking or sorting rolls.

The rolls, 15, are preferably of rubber composition, each molded on to a hollow mandrel or tube, 16, which is mounted for rotation upon a fixed shaft supported by the rotor casting. The mandrel of one roll of each pair has keyed to it a spur gear, 17, and a bevel gear, 7, which may be integrally formed, while the other roll of the pair carries only a spur gear, 17^a, meshing with the gear 17. Within the tube, 16, which carries the gear, 17, the shaft, 18, is reduced in diameter throughout most of its length, forming bearing surfaces for the tube only near its ends, and the extreme end portions of said shaft, 18, are lodged respectively in a hole or socket, 19, found in the central portion of the rotor casting and in a hole, 20, at the outer end of one of the arms of said casting. Preferably, the shaft, 18, is hollow throughout its length, with radial openings, 21, leading to the bearing surfaces which may be spirally grooved in any well-known manner for distributing lubricant. Such lubricant may be supplied from an oiler or grease cup, 22, secured in the outer end of the shaft, 18.

The tube or mandrel, 16, of the other roll is carried by a shaft, 23, which is also reduced throughout much of its length, but which has portions near its ends fitted to serve as bearings for the tube, 16. The extreme end portions, 24 and 25, of the shaft, 23, are slightly eccentric with respect to the bearing surfaces; the part, 24, is supported in a socket, 26, in the rotor casting, while the part, 25, is enlarged by the addition of a tight sleeve or bushing, 27, occupying a hole, 28, in the outer end of the rotor arm adjacent to hole 20 and parallel thereto. This bushing, 27, is enough larger than the bearing portions of the shaft, 23, to require that the hole, 28, shall be large enough to permit in-

sertion or withdrawal of the shaft, 23, therethrough. The shaft, 18, is similarly inserted or withdrawn through the hole, 20, in assembling the machine or removing the rolls for 5 replacement or repair.

By virtue of the eccentricity of the parts, 24 and 25, the roll carried by the shaft, 23, may be adjusted toward or from the other roll by slightly rotating the shaft, 23, in its 10 mountings; and such adjustment is effective for determining the grading of the beans or other grain which the machine will accomplish. The shaft, 18, is held in position by a set screw, 29, and a similar set 15 screw, 30, is provided to engage the bushing, 27, of the shaft, 23, for holding the shaft at any position of adjustment. The grease cup, 22, being fixed tightly on the end of the shaft, 23, may be used as a knob for turning 20 it in making the eccentric adjustment.

As shown in Figure 1, the central portion of the rotor casting includes a downwardly facing beveled gear, 31, which meshes with the drive pinion, 32, on a shaft, 33. The 25 shaft is journaled in a bearing, 34, formed as a part of the flared casting, 5, in an outboard bearing, 35, beyond which the shaft may be fitted with a pulley, 36. For driving the machine by hand the hand crank, 37^a, 30 may be applied to the shaft, 33, as shown in dotted lines, or a crank handle, 37, may be secured to the rim of the feed hopper, 13, said hopper being mounted upon the 35 standing flange, 11, of the rotor by means of brackets, 53, secured to said flange by bolts, 54. It will be evident that as the drive shaft, 33, is turned, the meshing of the gears, 31 and 32, will cause the rotor to revolve in horizontal plane, thus generating centrifugal force in the beans or other grain piled 40 upon the bottom plate, 12, and causing them to travel outwardly for discharge through the ports, 14, and thence along the radially extending roll surfaces.

I find that improved results are obtained, particularly in a small machine of this kind, by inclining the roll axes slightly upward from their inner to their outer ends,—say about five degrees from the horizontal,—so 45 as to somewhat retard the travel of the grains over the rolls and allow more time for the culls, stones and dirt to be carried away by frictional contact with the rolls. Such material is collected in the inner hopper, 38, while the smooth grain which successfully travels the full length of the roll surfaces is discharged through openings, 39, formed between the ends of the rolls, 15, and the bearings in which their shafts are 50 lodged, and leading directly to the outer hopper, 40, whose discharge pipe, 41, may be connected to any convenient receptacle as desired.

Each radial arm of the rotor casting extending outwardly from the annular wall,

11, of the central hopper is formed at its sides with downwardly curving portions, 42, and with an open slot, 43, in the middle of its top surface, through which the travel of the grains in a trough formed by the 70 rolls may be observed. For controlling this travel and holding the grains close to the surfaces of the rolls, a series of adjustable guard fingers, 44, are mounted to project through the slots, 43, and are connected by 75 a ring, 45, encircling the flange, 11. Two or more of these fingers, 44, may be slotted at their vertical portions which lie against the flange, 11, so that, by means of clamp screws, 46, they can be adjustably secured at 80 the desired distance from the roll surfaces. At each side of the slot, 43, on the under side of the roll cover, I prefer to provide guard ribs, 47, extending fairly close to the upper side of each roll, 15, to prevent the 85 grains from bouncing over the rolls when agitated in their outward travel along them. At the inner ends of these ribs, 47, a depending guard flange, 48, extends transversely adjacent the inner side of the port, 90 14, and just outside the teeth of the gears, 17 and 18, to prevent any material being thrown back between gears.

To further direct the travel of the grain, 95 the upper surface of the feed hopper within in the flange, 11, may be formed with low ribs or grooves, 49, extending at each side of the ports, 14, and feed grooves, 50, may be provided leading into each of said ports, 14. These features are not essential, but they comprise corrugations in the hopper bottom which tend to guide the grains to the 100 ports, 14, in single file so that the rolls may act upon them individually.

By making the roll covers as integral arms 105 of the rotor, the cost of manufacture of a machine of this character is greatly reduced and adjustment or repair of the individual rolls is facilitated because the entire rotor with the rolls assembled therein may be 110 lifted off from the center column, 1, and turned upside down on the floor or bench, whereupon the rolls are immediately available for inspection, cleaning or adjustment. As already described, any roll may be 115 removed merely by loosening the set screw, 29 or 30, and withdrawing the supporting shaft, 18 or 23, as the case may be. Preferably, the gears are loosely slipped on to the 120 tubular mandrels, 16, and retained merely by Woodruff keys, so as to be readily removable if desired, but it is also feasible to knurl the mandrels and make the gears a tight fit. The roll bearings, being within 125 the tubes, 16, are quite thoroughly protected from the dust and dirt which is present during the sorting process, and the lubrication coming from within the shafts, 18 and 23, meets with no interference by reason of this dirt; such lubricant as may work out at the 130

ends of the tubes, 16, tends rather to accumulate a limited quantity of dust which hardens and thus seals the ends of the tubes.

As shown, the feed hopper, 13, is fitted at its discharge opening with a vertically adjustable sleeve, 55, by which it becomes possible to regulate the height of a conical pile of grain which will accumulate upon the plate, 12, and thus regulate the diameter of the base of such pile to vary the rate of feed. I find that making the hopper, 13, rotatable with the rotor frame gives a more even feed from said hopper than when it is fixedly mounted above the machine. Apparently the centrifugal force acting on the grain in the hopper tends to retard its flow through the central discharge mouth by holding it back from said mouth in opposition to the force of gravity.

In using a machine of this type for sorting clover seed which is much smaller than beans or peas and nearly always contains a mixture of buckhorn which is a long narrow grain, I propose to turn the rotor in reverse direction so as to cause each pair of rolls to rotate away from each other at their upper sides instead of toward each other as for sorting beans. For such use a covering of felt or canvas may be substituted for the rubber rolls, 15, if desired, and the eccentric means of adjusting the rolls may be taken advantage of for setting them quite close together in view of the small size of the clover seed. In most machines of this general type, it has been common practice to mount the rolls of each pair with the axis of one roll in a plane somewhat above the axis of the other so that the upper roll would act as an impeller for carrying the grain around as the rotor revolves. In refining my machine I have found that the rotor speed of revolution need not be great and that the rolls can be mounted with their axes in a common plane. This feature is of special value when the machine is reversed, as just described, for use with clover seed where the culled matter is not fed between the two rolls but is carried over them by frictional engagement.

I claim:

1. In a centrifugal grain-sorting machine, a rotor frame comprising a roll cover casting common to all the sorting rolls and formed with depending integral portions in which the roll shafts are mounted.

2. In a centrifugal grain-sorting machine, a rotor frame comprising an upwardly open central hopper and a plurality of radially extending downwardly concave arms serving as covers for the respective pairs of rolls and means for supporting said rolls on the rotor frame on said covers.

3. In the combination defined in claim 2, the hopper having discharge ports remote from its center and disposed respectively

above the troughs formed between the rolls of the several pairs.

4. In the combination defined in claim 2, said roll covers having radially extending slots, each disposed above one of the troughs between a pair of rolls to permit observation of the grain therein.

5. In a centrifugal grain-sorting machine comprising a pair of rolls geared together in radial arrangement with respect to a vertical axis and a frame by which said rolls are carried for revolution about said axis, said pair of rolls forming a trough extending radially, and a control finger arranged for vertical adjustment over said trough for regulating the flow of grain therethrough.

6. In the combination defined in claim 5, said frame including an upstanding annular flange defining a central feed hopper with a slotted roll cover extending outwardly from said flange and the control finger being supported by adjustable securing means on said flange, and projecting through the slot toward the rolls.

7. In a centrifugal grain sorting machine comprising a plurality of rolls geared together in pairs in radial arrangement about a vertical axis, and a frame by which said rolls are carried for revolution about said axis, each pair of rolls forming a trough extending radially, said frame including an upstanding annular flange defining a central feed hopper; and control fingers supported on said flange for vertical adjustment over said troughs to regulate the flow of grain therethrough, together with means encircling said flange connecting the fingers for simultaneous adjustment.

8. In a grain-sorting machine including a pair of yielding rolls geared together and extending adjacent each other in parallel relation, a shaft for each roll fixed in a frame and a tubular core on which the yielding material of each roll is secured and which is journaled for rotation on the fixed shaft.

9. In the combination defined in claim 8, said machine including a frame casting having a hole and a socket axially aligned to receive respectively the opposite ends of the shaft and means for locking the shaft therein.

10. In the combination defined in claim 8, said machine including a frame casting having a hole and a socket axially aligned to receive respectively the opposite ends of the shaft and means for locking the shaft therein, said casting including opposing shoulders adjacent the hole and the socket respectively and the tubular core of the roll being fitted between said shoulders.

11. In the combination defined in claim 8, said shaft having a passage for lubricant leading from one end of the shaft inwardly with an outlet branch extending to the bearing surface upon which the roll core turns.

12. In the combination defined in claim 8,

the shaft being reduced in diameter between its ends to form bearing surfaces of limited longitudinal extent for the roll core.

13. In the combination defined in claim 5 8, one shaft of each pair having eccentric end portions engaging a hole and socket of the frame whereby rotative adjustment of the shaft will vary the distance between the rolls of the pair.

14. In the combination defined in claim 8, one shaft of each pair having eccentric end portions engaging a hole and socket of the frame whereby rotative adjustment of the shaft will vary the distance between the rolls 15 of the pair and means on the frame for securing said shaft at any position of adjustment.

15. In the combination defined in claim 8, the inner ends of the tubular cores extending 20 beyond the yielding material and the gears connecting the rolls of each pair being keyed to said extending end portions of the cores to permit slidable removal of said gears from said cores.

16. In the combination defined in claim 8, the inner ends of the tubular cores extending also beyond the yielding material and the 30 gears connecting the rolls of each pair being keyed to said extending end portions of the cores to permit slidable removal of said gears from said cores, said gears being stopped against the yielding material of the rolls when positioned for operation on said cores.

17. In a centrifugal grain-sorting machine 35 which includes a plurality of yielding rolls geared together in pairs and extending in radial relation to a vertical axis, a rotor frame comprising a roll cover casting common to all the sorting rolls and formed with depending 40 portions in which fixed shafts are mounted on the covers, each roll having a tubular core on which the yielding material is secured, said core extending beyond the ends of said yielding material and being rotatably carried by one of said fixed shafts.

18. In a centrifugal grain sorting machine 50 which includes a plurality of yielding rolls geared together in pairs and mounted in radial relation to a vertical axis for revolution about the same, a feed hopper mounted to revolve with said rolls with its axis co-inciding with said vertical axis of revolution, a fixed master gear centered at said vertical axis, and pinions on the rolls meshing with 55 said gear for deriving motion as the rolls revolve; a carrier frame for the rolls to which said feed hopper is secured, and a handle on the hopper for turning said frame.

19. In a centrifugal grain sorting machine 60 which includes a plurality of yielding rolls geared together in pairs and mounted in radial relation to a vertical axis for revolution about the same, a feed hopper mounted to revolve with said rolls with its axis co-65 inciding with said vertical axis of revolution,

tion, the rotatably mounted frame serving as a carrier for said rolls and fixedly supporting the feed hopper, together with a handle on said hopper for turning the carrier.

20. In a centrifugal grain-sorting machine 70 which includes a plurality of yielding rolls geared together in pairs and mounted in radial relation to a vertical axis for revolution about that axis, a substantially flat distributing plate centrally disposed with respect to the rolls, a feed hopper supported above said plate for discharge thereto, and a vertically adjustable sleeve at the discharge mouth of the hopper.

21. In a centrifugal grain-sorting machine 75 which includes a plurality of yielding rolls geared together in pairs and mounted in radial relation to a vertical axis for revolution about the same, a central distributing plate associated with said rolls, and a feed 80 hopper disposed above said plate, with means for adjusting the discharge mouth of said hopper toward and from the plate.

22. In a centrifugal grain-sorting machine, a centrally fixed post, a central master gear having its hub secured to said post below the upper end thereof, a rotor frame in which the sorting rolls are carried, having a central hub rotatably engaging the upper end of the post with a thrust bearing interposed between the hub of the rotor and the hub of the master gear, the central portion of said rotor frame comprising a distributing hopper covering the end of the post and extending over the inner ends of the rolls with feed ports leading thereto.

23. In the combination defined in claim 22, said rotor frame including outwardly extending portion serving as covers for the respective pairs of rolls and also supporting 105 said rolls in operative relation to the master gear.

24. In a centrifugal grain-sorting machine which includes a plurality of yielding rolls 110 geared together in pairs and mounted in radial relation to a vertical axis for revolution about the same, the axes of both rolls of each pair being disposed at the same elevation in respect to said vertical axis.

25. In a centrifugal grain sorting machine 115 which includes a plurality of yielding rolls geared together in pairs and mounted in radial relation to a vertical axis for revolution about that axis, means to impart rotation to the rolls about their own axes by said revolution about said vertical axis and means for feeding grain onto such rolls near their inner ends for travel outward over the rolls under centrifugal force; said rolls being inclined slightly upward in the direction of 120 such travel.

In testimony whereof, I have hereunto set my hand at Chicago, Illinois, this 6th day of April, 1923.

RUSSELL V. JUDSON.
